DRIP DISPENSER

Pauline Annie Jaschke, La Grange, Tex.

Application June 20, 1939, Serial No. 280,181

7 Claims. (Cl. 221—148)

My invention relates generally to manually controlled liquid measuring and dispensing containers, and particularly to a container for dispensing fluid by measured dripping, and an important object of my invention is to provide a simple and efficient arrangement of this character which greatly facilitates the accurate mixing of two or more fluids.

More specifically, I have evolved and produced a valved material containing and measuring device in the form of an attachment for a mixing bowl, crock or equivalent receptacle, said device being characterized by a nozzle-equipped material dispensing container, this having bracket means or the like attachable to the wall of the crock to dispose the nozzle within the limits of the crock, there being simple and efficient bodily turnable and removable means in the container for selectively regulating the amount of the liquid discharged through the spout.

Other important objects and advantages of my invention will appear in the following description of the appended drawing showing a preferred embodiment of the invention.

25 In the drawing:

Figure 1 is a general sectional side elevational view of said embodiment.

Figure 2 is an elevational view looking from left to right in Figure 1, the view being partly broken away to show the cooperation of the handle with the drip measuring indicia.

Figure 3 is a top plan view of Figure 2.

Referring in detail to the drawing, the numeral 5 generally designates the chosen embodiment which comprises a main cylindrical casing or container 6 of the required size and diameter, which is of suitable material and is provided on opposite sides with volume indicating graduations 7 and 8, respectively. The invention is particularly well illustrated in connection with a container 6 of a two-cup capacity, and if desired the container 6 may be of opaque material and the various indicia marked on the inner side. The bottom 9 of the container is perfectly plain except for a declining drainage channel 10 leading from adjacent one side of the container toward and terminating at the depending discharging nipple 11, so as to convey the fluid toward the nipple. The nipple 11 is exteriorly threaded as indicated by the numeral 12 and on this is threadably mounted the spout 13 which has a laterally projecting and downwardly facing nozzle 14. Depending from the bottom 9 of the container adjacent the spout 13 is a clamp mounting arrangement which consists of a first stationary bracket

15 and a second stationary bracket 16, the latter having threaded therein a clamping screw 17, this arrangement providing for mounting the embodiment of the invention on the rim or edge of a crock or other container in which the liquid from the present invention is to be dripped at a controlled rate, so that the same will not extend too far over the crock and interfere with mixing operations in the crock.

Fitting snugly but rotatably and vertically slidably within the interior of the casing 6 is a false bottom 18. This false bottom is flat cylindrical in form as indicated in Figure 1 of the drawing, and reaches to only a fractional portion of the height of the interior of the container 6, and has formed in the bottom thereof adjacent one side, the graduated drip regulating openings 19, 20, and 21, in suitable size and number and adapted to be selectively registered with the opening in the nipple 11. For selectively positioning the openings in the false bottom relative to the nipple 11 there is provided a handle 22 which is in the form of a rod secured to the upper edge of the flange of the false bottom, and to project above the upper edge of the container 6, the handle being located on the false bottom and in position diametrically opposite the position of the openings 19, 20 and 21. A hand-hold or knob 23 is provided on the upper end of the handle so that the false bottom may be easily removed for cleaning purposes and the false bottom may be easily rotated to select the rate of dripping of the contents of the container from the false bottom into the nipple 11. Indicia 24 disposed around the upper edge of the container 6 are so placed as to have reference to the handle 22 so as to enable the user to conveniently and selectively position the false bottom to register the corresponding one of the holes therein with the spout. The indicia 25 when occluded by the handle 22 indicates that the false bottom is so positioned in the container that no one of the mentioned holes in the false bottom is registered with the nipple 11, and no dispensing of fluid from the container is taking place, since in that position of the false bottom, all of the holes 19, 20 and 21 are closed by the imperforate portion of the bottom 9 of the container.

Although I have shown and described herein a preferred embodiment of my invention, it is to be definitely understood that I do not desire to limit the application of my invention thereto, and any change or changes may be made in the materials and in the structure and arrangement of the

parts, within the spirit of the invention and the scope of the subjoined claims.

Having described the invention, what is claimed as new is:

- 5 1. A device of the character described comprising a container having a bottom formed with an eccentric fluid discharge port, a false bottom resting on said first named bottom and formed with a circumferential series of drip openings 10 graduated in size, and handle means on said false bottom for moving said false bottom to bring selected ones of said drip openings into registry with said discharge port.
- 15 2. A device of the character described comprising a container having a bottom formed with an eccentric fluid discharge port, a false bottom resting on said first named bottom and formed with a circumferential series of drip openings graduated 20 in size, and handle means on said false bottom for moving said false bottom to bring selected ones of said drip openings into registry with said discharge port, said false bottom consisting of a relatively shallow cylindrical tray having said handle means projecting vertically therefrom to 25 a point above the upper end of said container.
- 30 3. A device of the character described comprising a container having a bottom formed with an eccentric fluid discharge port, a false bottom resting on said bottom and formed with a circumferential series of drip openings graduated in size, and handle means on said false bottom for moving said false bottom to bring selected ones of said drip openings into registry with said discharge port, said false bottom consisting of a 35 relatively shallow cylindrical tray having said handle means projecting vertically therefrom to a point above the upper end of said container, graduations on the upper part of said container relative to which said handle means is positioned for selecting the drip openings to be registered with said discharge port.
- 40 4. A device of the character described comprising a container having a bottom formed with an eccentric fluid discharge port, a false bottom 45 resting on said bottom and formed with a circumferential series of drip openings graduated in size,

and handle means on said false bottom for moving said false bottom to bring selected ones of said drip openings into registry with said discharge, the bottom of the container having a declining portion leading to said discharge port. 5

5. A device of the character described comprising a container having a bottom formed with an eccentric fluid discharge spout, a false bottom resting on said bottom and formed with a circumferential series of drip openings graduated 10 in size, and handle means on said false bottom for moving said false bottom to bring selected ones of said drip openings into registry with said discharge spout, and clamp means depending from said bottom for mounting the device on the edge 15 of a crock or the like with said discharge spout located within the crock or the like.

6. In a material containing, dispensing and measuring device of the class described, a material container open at its top and including a bottom having a material discharge spout, a valving plate removably mounted for oscillation in said container and resting on the bottom of the container, said plate being provided with a plurality of selectively usable proportionately 20 different material discharge openings registerable with said spout, a lifting and operating handle attached to and rising from said plate and accessible through the open top of the container, and indicia provided on the container, the handle being selectively registerable therewith to facilitate complete closing of the spout by the plate, or selective positioning of the openings in the plate in alignment with the spout. 25

7. As a new article of manufacture and a component part of an assemblage of the class described, a disk-like valving plate having graduated selectively usable liquid discharge openings formed therein, an annulus carried by the plate cooperating therewith in forming a tray-like receptacle, and a handle attached to and rising from said annulus to facilitate handling the receptacle in the manner and for the purposes described. 40
